Primary Examiner—Doris Clark**Attorney, Agent, or Firm**—Pearne, Gordon, McCoy & Granger LLP**[57] CLAIM**

The ornamental design for an adjustable swimming pool ladder, as shown and described.

DESCRIPTION

FIG. 1 is a perspective view of an adjustable swimming pool ladder, showing my new design;

FIG. 2 is an exploded view thereof;

FIG. 3 is a fragmentary front elevational view thereof;

FIG. 4 is a fragmentary top plan view thereof;

FIG. 5 is a fragmentary side elevational view thereof;

FIG. 6 is a fragmentary back elevational view thereof;

FIG. 7 is a fragmentary bottom plan view thereof.

The broken lines showing a ladder and platform assembly is for illustrative purposes only and forms no part of the claimed design.
